UNITED STATES PATENT OFFICE.

THOMAS BEMIS, OF INDIANAPOLIS, INDIANA.

PNEUMATIC-DESPATCH APPARATUS.

1,090,375.

Specification of Letters Patent. Patented Mar. 17, 1914.

Application filed November 13, 1911, Serial No. 660,106. Renewed September 15, 1913. Serial No. 789,898.

To all whom it may concern:

Be it known that I, THOMAS BEMIS, a citizen of the United States, and a resident of Indianapolis, county of Marion, and State 5 of Indiana, have invented a certain useful Pneumatic-Despatch Apparatus; and I do hereby declare that the following is a full, clear, and exact description thereof, reference being had to the accompanying drawings.

The object of this invention is to improve the construction of pneumatic despatch apparatus of the kind disclosed in my former applications for Letters Patent, Serial No. 15 428,734, filed April 23, 1908 and Serial No. 435,414, filed May 28, 1908, particularly the latter. In this type of pneumatic despatch apparatus the operating expense of the apparatus is reduced by limiting the operation 20 thereof to the portion of the apparatus which is in actual use and to the actual time when it is in use. Hence, means are provided for retarding the closing of the door or main valve and timing such closure so as to insure 25 the conveyance of the carriers through the apparatus to its destination. The door or main valve is closed by a weighted member which is controlled by a gravity piston, and the descention of said piston is controlled by 30 timing means and the return by the suction in the despatch apparatus; and the return of the piston also returns the weighted member from its valve closing position.

The nature of the invention will be understood from the accompanying drawings and the following description and claims:

In the drawings, Figure 1 is a plan view of the terminal. Fig. 2 is a central vertical section on the line 2—2 of Fig. 1, showing 40 the door closed. Fig. 3 is a perspective view of the paddle and trip lever for opening the air valve. Fig. 4 is a rear elevation of the terminal. Fig. 5 is the same as Fig. 2, with the door in open position preliminary to its 45 closing movement. Fig. 6 is a vertical section on the line 6—6 of Fig. 2. Fig. 7 is a horizontal section on the line 7—7 of Fig. 2. Fig. 8 is a section on the line 8—8 of Fig. 9. Fig. 9 is a plan view of the lower end member 50 of the timing cylinder. Fig. 10 is a vertical section of the parts showing the means for holding open the valve which controls the communication between the insert valve and timing cylinder. Fig. 11 is a section on 55 the line 11—11 of Fig. 10. Fig. 12 is the

same as Fig. 10, showing the parts in a different position. Fig. 13 is a horizontal transverse section on the line 13—13 of Fig. 14. Fig. 14 is a rear elevation of the device as shown in Fig. 2. Fig. 15 is a vertical section on the line 15—15 of Fig. 1.

In detail 10 represents a carrier and inlet tube of the terminal at the central or cashier's station of the pneumatic despatch apparatus. The mouth of the terminal is 65 closed by a door or main valve 11, which has a pair of ears 12 pivoted on a pin 13 on an extension 14 from the tube 10. The main valve 11 is closed by the weighted member 15, which is fulcrumed on the pin 13, and when said weighted member descends, it engages a rear flange 16 of the main valve 11 and closes the valve. Fig. 5 shows this part 70 of the mechanism when the closing movement of the valve 11 has just started. It is 75 to be understood that after the main valve has thus been closed, said weighted member 15 is lifted by means hereafter explained to a position shown in Fig. 2 so as not to interfere with the opening of the valve. The 80 main valve will be held closed by the suction in the apparatus until it is opened by the operator who strikes the projection 56 of the main valve and throws it open and inserts a carrier, not shown. The construction of the 85 apparatus is such as to hold the door open long enough for that carrier to reach its destination, and to this end the release of the weighted member 15 from its elevated position 90 is timed.

Assuming the parts to be in their condition immediately after the main valve has been closed by the weighted member, said weighted member is moved from its lower position to its upper position by the piston 95 22 in the cylinder 21, which cylinder is secured to a casting 121 and said casting holds and surrounds the tubular portion 10 of the terminal, see Fig. 5. The cylinder 10 is parallel with the inlet passageway of the 100 terminal, and it has a bottom member 20 which closes its lower end and through which a piston rod 25 moves. Said piston rod extends loosely through an opening in the upper end of a bracket 26, which is pivoted at 27 to the weighted member 15, and the lower end of the piston rod 25 has an enlarged portion 28, so that when the piston goes upward this enlarged portion 28 of the piston rod engages the top of the bracket 105 110

26 and lifts the weighted member 15 to its elevated position, as shown in Fig. 2, and when the weighted member reaches the elevated position, the projection 18 therefrom is caught by the catch lever 17, which is pivoted between its ends at 19 between ears extending down from the bottom member of the cylinder 21.

The piston 22 is lifted by suction through 10 the feed line or air exhausting means 133 from a suction drum (not shown). To this end there is a conduit or air passageway leading from the feed line 133 to the upper end of the cylinder 21. It consists of a chamber 15 32, which is in communication with the feed line 133, and by means of a port 34 is also in communication with the chamber 31 above the chamber 32, and the chamber 31 is in communication with the upper end of the 20 cylinder 21 through a tube 30. The main portion of this tube is shown by dotted lines in Fig. 2. The exhaust of air through said conduit from the upper end of the cylinder 21 causes outer air to enter the 25 lower end of said chamber through a port 60 in the bottom member 20 of said cylinder and forces the piston 22 to the upper end of the cylinder. The port 60 is closed by a ball valve 61, which is held from escape by 30 the bar 62. This ball valve 61 tends to resist somewhat the incoming air, and, therefore, prevents too rapid upward movement of the piston 22.

The port 34 between the two chambers 31 and 32 is opened and closed by the air outlet valve 36 on the stem 37 which extends down into a chamber in the lower part of the terminal and to one side of the carrier passageway. It there rests normally on 35 one arm of a trip lever 38. Said lever is actuated by a projection 39 on the end of a paddle 40, which is fulcrumed at 41 within the terminal and to one side of the carrier passageway, and so as to extend across the 40 terminal, as shown in Fig. 2, when the main valve is closed and there is no carrier or air movement through the terminal. In that position it holds the valve 36 open and permits the air exhaust in the apparatus to 45 lift the piston 22 and thereby the weighted member 15. The valve 36 is held open after it has been moved upward by a trip lever 50 fulcrumed at 51 to the intermediate portion 50 121 of the apparatus and having a biting edge 52 adapted to engage corrugations 53 on the valve stem 57 and hold it in its upper position. The outer end of the trip lever 50 is yoked and extends astride the piston rod 25. When the piston reaches its 55 upper limit of movement, it causes the disengagement of the catch 50 from the valve stem 37 by reason of the bracket 26 being lifted up against the outer end of the catch lever 50.

60 Assuming the parts now to be in the posi-

tion shown in Fig. 2, as a result of the foregoing part of the operation, when the main valve is opened and a carrier inserted, the paddle 40 is moved out of the carrier passageway to one side and releases the trip lever 38, so that the valve 36 closes. The main valve is then open and the air moves through the terminal and apparatus for the conveyance of the carrier. The door must, however, be left open long enough to permit the carrier to reach its destination, and this is accomplished by the following means: The main valve will not close until the weighted lever 15 drops down, and it cannot drop down as long as it is held up by the catch 17 until dislodged by descent of the piston which is allowed to descend slowly by air entering the upper end of the cylinder 21 slowly through the passageway 30 and chamber 31 and the horizontal passageway 130 leading from a vent 131, see Fig. 13. This vent is controlled by a valve 132 so as to admit air slowly. Air escapes from the underside of the piston 22 by reason of the loose fit of the piston rod 25 in the lower end 20 of the cylinder, for then the ball valve 61 is closed. Said valve 61 co-operates with the vent 131 in delaying and timing the downward movement of the piston 20 so as to give the carrier, which has been inserted, time to reach its destination. When the piston 22 reaches its lower limit of movement, it engages the pin 23 extending through the bottom member 20 of the cylinder, and said pin releases the catch lever 17, so that the weighted member 15 drops down and closes the main valve after the carrier has reached its destination. When the operator inserts a second carrier before the main valve has shut, after a previous carrier has been inserted, so that the paddle 40 cannot drop down across the passageway and open the air outlet valve 36, an additional trip 65 is provided so as to be engaged by the second carrier, and it lifts the valve 36. The trip 65 is mounted in the lower part of the terminal and its free end projects into the main passageway and is maintained in such position by gravity. It is curved backwardly and outwardly so that the extreme end thereof will engage a downwardly extending arm of the trip lever 38 and when the trip is struck by a carrier, it will actuate trip lever 38 from the position shown in Fig. 5 to the position shown in Fig. 2, and thus elevate 115 and unseat the valve 36, the same as if paddle 40 had dropped across the terminal passage. However, when the second carrier is not inserted before the main valve is closed, such trip is unnecessary.

120 A stop 70 is provided which is pivoted at 71 in an extension 72 of the terminal so that the free end of said stop falls by gravity and projects into the passageway. As the carrier goes up it pushes the stop 70 out of the 125 130

way to one side, but if the carrier should happen to drop back after it has started up, it would be caught by the stop 70. This occurs when the operator at the other end of the line opens her valve before the carrier gets out of the vertical portion of the despatch tube joining the terminal where the carrier was inserted. Often the operator at the other end of the line opens and closes her valve so quickly that the paddle 40 can only get started on its downward movement across the passageway through the terminal, and it is desirable that any such sliding movement of the paddle shall be sufficient to open the valve 36, and for that reason one arm of the trip lever 38 is made longer than the other, long enough to project into close proximity with the projection 39 of the paddle 41, so that said projection 39 will begin to actuate the arm and trip 38 as soon as the paddle starts downward, and the catch lever 50 engaging the valve stem 37 will hold the valve 36 open to the end to which it may have been opened by such partial movement 25 of the paddle 40. In the practical operation of the device this is a very important feature, for otherwise often the valve 36 would not be opened by the quick opening and closing of the operator's valve at the other end 30 of the line, and in such event the piston 22 would not be lifted and the device not operate.

Sometimes the carrier gets clogged in the line, as when the cashier lets papers stick out 35 of the carrier and for other reasons. In that event it is necessary to apply an air exhausting means at the inlet of the terminal and in order to draw the carrier backward through it and out. It is, therefore, necessary, in such event, that the paddle 40 and the trip 65 and catch 70 should all be out of the path of the returning carrier. Therefore, the paddle 40 is loosely mounted on the pin 41 and one side of the paddle 40 has a 45 rectangular recess 140 in it in which a squared portion 175 of the pivot 41 is adapted to be inserted by pushing the pivot to the right from the position shown in Fig. 6. To give it this movement, however, it is necessary to remove the locking pin 76, which extends through a flange 75 on the terminal into the pin 41. By removing the locking pin 76 and pushing the pivot pin 41 to the right one can readily turn the paddle 40 to 50 its upper position out of the way of the carrier, and then by clamping the nut 77 which screws on said pivot 41 the paddle will be held in that position. Likewise the trip 60 is turned out of the way by an arm 166 on the end of the pivot 66 and it is held in that outer position by a locking pin 79 extending into the pivot 66 and through a flange 78. The stop 70 is also turned out of the way by turning its pivot 71 and held out in a similar 55 way.

I claim as my invention:

1. A pneumatic despatch apparatus including a terminal having an inlet tube, a main valve for closing the same, a weighted member for closing said main valve, means actuated by the air exhaust in the apparatus for elevating said weighted member, means for catching said weighted member when elevated, and means actuated by said elevating means for releasing said catching means, and timing means for controlling the releasing movement of said elevating means. 70

2. A pneumatic despatch apparatus including a terminal having an inlet tube, an exhaust connection, an air cylinder provided with communication between the exhaust connection and the upper end of said cylinder and also provided with a reduced timing air inlet, a valve for opening and closing the communication between the exhaust connection and said cylinder, means operable within the terminal for opening said valve, a main valve for closing the inlet to the terminal, a weighted member for closing said main valve, a piston in said cylinder, a piston rod connected with said weighted member so as to lift it when the piston ascends, a catch for engaging and holding said weighted member in its upper position, and means actuated by the piston as it reaches its lower limit of movement for releasing said catch. 95

3. A pneumatic despatch apparatus including a terminal having an inlet tube, an exhaust connection, an air cylinder provided with communication between the exhaust connection and the upper end of said cylinder and also provided with a reduced timing air inlet and also having an air port at its lower end, a ball valve for closing the port and lower end of the cylinder, a valve for opening and closing the communication between the exhaust connection and cylinder, means operable within the terminal for opening said valve, a main valve for closing the inlet to the terminal, a weighted member for closing said main valve, a piston in said cylinder, a piston rod connected with said weighted member so as to lift it when the piston ascends, a catch for engaging and holding said weighted member in its upper position, and means actuated by the piston as it reaches its lower limit of movement for releasing said catch. 110

4. A pneumatic despatch apparatus including a terminal having an inlet tube, an exhaust connection, a main valve for closing the same, a weighted member pivoted to said terminal for closing said main valve, a vertical cylinder with the upper end in communication with the exhaust connection, a valve for controlling said communication, a valve-controlled inlet for air at the lower end of said cylinder, a piston in said cylinder, a piston rod operating through the 125 130

lower end of the cylinder, a connection between said weighted member and piston rod so that the piston rod will lift the weighted member but can return independently of the weighted member, a catch pivotally mounted in the lower end of the cylinder and adapted to engage and hold the weighted member when elevated, means extending through the lower end of the cylinder and adapted to be actuated by the piston at the lower end of its movement for releasing said catch, and means for slowly admitting air into the upper end of said cylinder.

5. A pneumatic despatch apparatus including a terminal having an inlet tube, an exhaust connection, a main valve for closing the same, a weighted member pivoted to said terminal for closing said main valve, a vertical cylinder with the upper end in communication with the exhaust connection, a valve for controlling said communication, a valve-controlled inlet for air at the lower end of said cylinder, a piston in said cylinder, a piston rod operating through the lower end of the cylinder and having an enlarged lower end, a bracket pivoted to said weighted member with an opening through the upper end thereof for said piston rod, a catch pivotally mounted to the lower end of the cylinder and adapted to engage and hold the weighted member when elevated, means extending through the lower end of the cylinder and adapted to be actuated by the piston at the lower end of its movement for releasing said catch, and means for slowly admitting air into the upper end of said cylinder.

6. A pneumatic despatch apparatus including a terminal having an inlet tube, a main valve for closing the same, a weighted member pivoted to said terminal for closing said main valve, an exhaust connection, a vertical cylinder with the upper end in communication with the exhaust connection, a valve for controlling said communication, a valve-controlled inlet for air at the lower end of said cylinder, a piston in said cylinder, a piston rod operating through the lower end of the cylinder, a connection between said weighted member and piston rod so that the piston rod will lift the weighted member but can return independently of the weighted member, a catch pivotally mounted to the lower end of the cylinder and adapted to engage and hold the weighted member when elevated, means extending through the lower end of the cylinder and adapted to be actuated by the piston at the lower end of its movement for releasing said catch, means for slowly admitting air into the upper end of said cylinder, and means within the terminal adapted to be moved by gravity when the movement of air diminishes in the terminal and cause the opening of the valve con-

trolling the communication between the cylinder and the air exhausting means.

7. A pneumatic despatch apparatus including a terminal having an inlet tube, a main valve for closing the same, a weighted member pivoted to said terminal for closing said main valve, an exhaust connection, a vertical cylinder with the upper end in communication with the exhaust connection, a valve for controlling said communication, a valve-controlled inlet for air at the lower end of said cylinder, a piston in said cylinder, a piston rod operating through the lower end of the cylinder, a connection between said weighted member and piston rod so that the piston rod will lift the weighted member but can return independently of the weighted member, a catch pivotally mounted to the lower end of the cylinder and adapted to engage and hold the weighted member when elevated, means extending through the lower end of the cylinder and adapted to be actuated by the piston at the lower end of its movement for releasing said catch, means for slowly admitting air into the upper end of said cylinder, a stem for the valve which controls the communication between the exhaust connection and the cylinder and provided with corrugations thereon, means for actuating said valve stem and lifting the same to unseat the valve, and a gravity actuated catch for engaging the corrugations in said valve stem when it is released and holding the valve open.

8. A pneumatic despatch apparatus including a terminal having an inlet tube, a main valve for closing the same, a weighted member pivoted to said terminal for closing said main valve, an exhaust connection, a vertical cylinder with the upper end in communication with the exhaust connection, a valve for controlling said communication, a valve-controlled inlet for air at the lower end of said cylinder, a piston in said cylinder, a piston rod operating through the lower end of the cylinder, a connection between said weighted member and piston rod so that the piston rod will lift the weighted member but can return independently of the weighted member, a catch pivotally mounted to the lower end of the cylinder and adapted to engage and hold the weighted member when elevated, means extending through the lower end of the cylinder and adapted to be actuated by the piston at the lower end of its movement for releasing said catch, means for slowly admitting air into the upper end of said cylinder, a stem for the valve which controls the communication between the exhaust connection and the cylinder and provided with corrugations thereon, means for actuating said valve stem and lifting the same to unseat the valve, a gravity actuated catch for engaging the corrugations in said

valve stem when it is raised and holding the valve open, said catch projecting into proximity with said piston rod so that the elevation of the piston rod will cause the release of said valve stem catch.

5 9. A pneumatic despatch apparatus including a terminal having an inlet tube, a main valve for closing the same, a weighted member for closing said main valve after it has been opened, an exhaust connection, a cylinder, a piston therein, means operated by the piston for controlling the action of the weighted member for closing the main valve, a conduit from the upper end of the cylinder through a valve chamber to the exhaust connection, a valve for closing said communication which is provided with a downwardly extending stem, a pivoted trip lever with one arm extending in position when actuated to elevate the valve stem and open the air outlet valve, a paddle fulcrumed within the terminal in position to be moved out of the path of the carrier by the air passing through the terminal, and a projection on said paddle engaging said trip lever and actuating the same to open the air valve after the paddle leaves the vertical position and starts downward across the passageway through the terminal.

30 10. A pneumatic despatch apparatus including a terminal having an inlet tube, a main valve for closing the same, a weighted member for closing said main valve after it has been opened, an exhaust connection, a cylinder secured to the terminal, a piston therein, means operated by the piston for controlling the action of the weighted member for closing the main valve, a conduit from the upper end of the cylinder through a valve chamber to the exhaust connection, a valve for closing said communication which is provided with a downwardly extending stem, a pivoted trip lever with one arm thereof extending in position when actuated to elevate the valve stem and open the air outlet valve, a paddle fulcrumed within the terminal in position to be moved out of the path of the carrier by the air passing through the terminal, a projection on said paddle engaging said trip lever and actuating the same to open the air valve after the paddle leaves the vertical position and starts downward across the passageway through the terminal, said valve stem having threads on it, a catch lever pivoted at one end with a biting edge for engaging the threads on the valve stem and supporting the valve stem and valve, and means for releasing said catch lever when said weighted member is elevated.

60 11. A pneumatic despatch apparatus including a terminal having an inlet tube, a main valve for closing the same, a weighted member for closing said main valve after it has been opened, an exhaust connection,

a cylinder, a piston therein, means operated by the piston for controlling the action of the weighted member for closing the main valve, a conduit from the upper end of the cylinder through a valve chamber to the exhaust connection, a valve for closing said communication which is provided with a downwardly extending stem, a pivoted trip lever with one arm thereof extending in position when actuated to elevate the valve stem and open the air valve outlet and having another and longer arm, a paddle fulcrumed within the terminal in position to be moved out of the path of the carrier by the air passing through the terminal, a projection on said paddle engaging the longer arm of said trip lever and actuating the same to open the air outlet valve after the paddle leaves the vertical position and starts downward across the passageway through the terminal, said valve stem having threads on it, a catch lever pivoted at one end with a biting edge for engaging the threads on the valve stem and supporting the valve stem and valve, and means for releasing said catch lever when said weighted member is elevated.

12. A pneumatic despatch apparatus including a terminal having an inlet tube, a main valve for closing the same, a weighted member for closing said main valve after it has been opened, an exhaust connection, a cylinder, a piston therein, means operated by the piston for controlling the action of the weighted member for closing the main valve, a conduit from the upper end of the cylinder through a valve chamber to the exhaust connection, a valve for closing said communication which is provided with a downwardly extending stem, a pivoted trip lever with one arm extending in position when actuated to elevate the valve stem and open the air outlet valve, a paddle fulcrumed within the terminal in position to be moved out of the path of the carrier by the air passing through the terminal, a projection on said paddle engaging said trip lever and actuating the same to open the air outlet valve after the paddle leaves the vertical position and starts downward across the passageway through the terminal, and an additional means projecting into the path of the carriers inserted therein which is in position when moved by said carrier to engage said trip lever and actuate the same.

13. A pneumatic despatch apparatus including a terminal having an inlet tube, a main valve for closing the same, a weighted member for closing said main valve after it has been opened, an exhaust connection, a cylinder, a piston therein, means operated by the piston for controlling the action of the weighted member for closing the main valve, a conduit from the upper end of the cylinder through a valve chamber to the exhaust con-

- nection, a valve for closing said communication which is provided with a downwardly extending stem, a pivoted trip lever with one arm extending in position when actuated to 5 elevate the valve stem and open the air outlet valve, a paddle fulcrumed within the terminal in position to be moved out of the path of the carrier by the air passing through the terminal, a projection on said 10 paddle engaging said trip lever and actuating the same to open the air outlet valve after the paddle leaves the vertical position and starts downward across the passageway through the terminal, and a stop pivotally 15 mounted outside the passageway in said terminal and opposite said paddle and adapted by gravity to project into the path of the carrier and arranged so that the carrier will force it out of said path but after the carrier 20 passes it will fall back and catch the carrier if it should return into the terminal.
14. A pneumatic despatch apparatus including a terminal having an inlet tube, a main valve for closing the same, a weighted 25 member for closing said main valve after it has been opened, an exhaust connection, a cylinder, a piston therein, means operated by the piston for controlling the action of the weighted member for closing the main 30 valve, a conduit from the upper end of the cylinder through a valve chamber to the exhaust connection, a valve for closing said communication which is provided with a downwardly extending stem, a pivoted trip lever with one arm extending in position 35

when actuated to elevate the valve stem and open the air inlet valve, a paddle fulcrumed within the terminal in position to be moved out of the path of the carrier by the air passing through the terminal, a projection on 40 said paddle engaging said trip lever and actuating the same to open the air valve after the paddle leaves the vertical position and starts downward across the passageway through the terminal, and means for clamping said paddle in its open position. 45

15. A pneumatic despatch apparatus including a terminal having an inlet tube, a main valve for closing the same, means for closing said main valve, a paddle fulcrumed within the terminal in position to be moved by gravity across the passageway therethrough and out of said passageway for controlling the main valve closing means, an additional trip fulcrumed in the terminal and adapted to project into the passageway therethrough and be actuated by an inserted carrier for controlling the main valve closing means, a stop projecting into the passageway into the terminal adapted to 50 catch a returning carrier, and means for holding said paddle, trip and stop out of the passageway through the terminal. 55

In witness whereof, I have hereunto affixed my signature in the presence of the 60 witnesses herein named.

THOMAS BEMIS.
